[57] CLAIM

The ornamental design for a respiratory therapy device, as
shown and described.

DESCRIPTION

FIG. 1 is a front perspective view of a respiratory therapy
device;

FIG. 2 is a front elevational view thereof;

FIG. 3 is a rear elevational view of the respiratory therapy
device;

FIG. 4 is a top plan view of the respiratory therapy device;

FIG. 5 is a bottom plan view thereof;

FIG. 6 is a left side elevational view of the respiratory
therapy device;

FIG. 7 is a right side elevational view of the respiratory
therapy device; and,

FIG. 8 is another front perspective view of the respiratory
therapy device, with an attachable breathing tube being
shown in broken lines for illustrative purposes only and
forming no part of the claimed design.
